UNITED STATES PATENT OFFICE.

FRANK MAGIDSON, OF BROWNSVILLE, PENNSYLVANIA, ASSIGNOR OF ONE-HALF TO
JACOB DAVIS, OF UNIONTOWN, PENNSYLVANIA.

ESCAPEMENT FOR SPRING-MOTORS.

1,212,789.

Specification of Letters Patent. Patented Jan. 16, 1917.

Application filed July 15, 1916. Serial No. 109,424.

To all whom it may concern:

Be it known that I, FRANK MAGIDSON, a citizen of the United States, and resident of Brownsville, in the county of Fayette and 5 State of Pennsylvania, have invented certain new and useful Improvements in Escape- ment for Spring-Motors, of which the following is a specification.

The primary object of this invention is to 10 provide escapement mechanism of simple and improved construction for imparting vibratory movement from a spring motor.

While the mechanism is designed primarily for rocking a cradle, it may be variously 15 employed for controlling the escapement of the power spring of a spring motor.

In the accompanying drawings, Figure 1 is a longitudinal sectional elevation of spring motor mechanism embodying the invention. 20 Fig. 2 is a cross sectional elevation of the mechanism, taken on line 2—2 of Fig. 3, and Fig. 3 is a section taken on line 3—3 of Fig. 2. Fig. 4 is a sectional plan taken on line 4—4 of Fig. 2.

25 Referring to the drawings, 2 designates a motor casing here shown rectangular in cross-section, and arranged centrally therein is a core which may be variously constructed but which in the preferred adaptation consists of the rotatable intermediate sections 3, 30 rotatable end section 4, and the opposite non-rotatable end section 5, the latter supported by the leg-forming pin 6 confined in the diagonally opposite corners of casing 2.

35 Where independently rotatable core sections are employed as here shown they may be mounted on and held in operative relation to each other by the rod or shaft 7. The central core sections are embraced by the 40 elongated coiled spring 8, one end of which is anchored to leg or support 6, and the opposite end is secured to the end core sections 4.

Secured to core section 4 is ratchet wheel 45 9, and secured to and extending outwardly from this wheel is short shaft 10. This shaft is rotatably mounted in casing head 11, and the projecting portion thereof is squared at 10' to receive a winding crank. The bearing 50 for shaft 10 comprises a hub 12 which projects from the inner side of head 11.

The escapement mechanism is interposed 55 between ratchet wheel 9 and casing head 11, and in the embodiment here shown consists of two radially disposed supports 13 and 14

which extend outwardly past opposite portions of the notched periphery of the wheel. Support 13 is immovably held, the inner portion 15 thereof embracing and rigid with hub 12. The support 14, disposed oppositely to support 13, has its inner portion enlarged at 16 and fitted to oscillate about hub 12, and the outer extremity of support 14 is projected through a slot in casing 2 as shown at 14' for transmitting vibratory movement to a cradle body or other device to be actuated by the motor.

Pivoted to the outer portion of support 13 is dog 17, and to the corresponding portion of support 14 is pivoted the reversely disposed dog 18. These dogs are of like construction, being angular in shape with the outer portions 17' and 18', respectively, thereof adapted to coöperate with the teeth of wheel 9. A free portion of each dog extends inwardly toward shaft 10 and hub 12, and secured thereto, respectively, are the outer ends of coiled springs 19 and 20. The inner end of spring 19 is secured to lateral extension 16' of enlargement 16 of the oscillating support 14, while the inner end of spring 20 is similarly secured to lateral extension 15' of enlargement 15 of fixed support 13. To accomplish this, enlargement 16 is slotted at 16'' to pass the lateral extension 15' of the fixed support. Support 14 is movably secured to the fixed support and guided by the screw and slot connections 21.

Operation: Upon imparting motion to the cradle or other body connected to the escapement mechanism, support 14 is caused to vibrate, and movement to the right from the position shown in Fig. 2 causes spring 20 to move dog 18 out of engagement with the ratchet wheel, this movement resulting from the fact that the inner end of spring 20 is immovably held at 16' while dog 18 is moving with support 14. This same movement of support 14 flexes spring 19 in such manner as to throw dog 16 into engagement with wheel 9, this movement resulting from the fact that the inner end of spring 19 moves with support 14, thereby causing dog 17 to pivot in the manner described. On the backward oscillation of support 14, *i. e.*, from right to left, the above described operation is reversed, at such time the action of spring 20 causing dog 18 to engage the ratchet wheel, while force is so applied to spring 19 as to cause it to disengage dog 17.

Upon stopping the oscillation of the cradle or other body, the escapement mechanism is brought to a standstill, and the dog then in engagement with the ratchet wheel will hold the motor stationary until motion is again imparted to the cradle or other body. The spring motor mechanism *per se* herein disclosed forms the subject matter of my application filed July 15, 1916, Serial No. 109,423.

10 I claim:—

1. The combination of a ratchet wheel, two supports adjacent opposite portions of the wheel periphery with one support immovable and the other adapted to oscillate concentrically with the wheel, dogs pivoted to the supports and adapted to coöperate with opposite portions of the wheel, and means connecting the dogs with the vibrating support whereby they are actuated simultaneously in reverse directions with one dog engaging the wheel and the other dog disengaging the same.
2. An escapement mechanism comprising a spring impelled ratchet wheel, two pivoted dogs adapted to coöperate with different portions of the wheel, an immovable support for one dog, an oscillating support for the other dog, an actuating spring for each dog connected at one end thereto, and holding devices for the opposite ends of said springs, the holding device for that spring which co-operates with the dog mounted on the immovable support being adapted to oscillate, and the holding device for that spring which co-operates with the dog mounted on the oscillating support being immovably held.
3. An escapement mechanism comprising a spring impelled ratchet wheel, two sup-

ports extending radially and in different directions from the wheel center, one of the supports being immovable and the other support adapted to oscillate about the wheel center, two dogs pivoted respectively to the supports and adapted to coöperate with different portions of the wheel periphery, an actuating spring for each dog connected thereto and extending toward the wheel center, and securing devices for the inner ends of the springs, the securing device for the spring of that dog pivoted to the immovable support being adapted to vibrate, and the securing device for the spring of that dog pivoted to the vibrating support being immovable.

4. The combination of a spring impelled ratchet wheel, two supports extending radially from the wheel center with one support adapted to oscillate about said center and with the other support immovable, two dogs pivoted to the respective supports and adapted to coöperate with opposite portions of the wheel periphery, actuating springs secured at their outer ends to the dogs and extending inwardly toward the wheel center, holding means on the immovable support for the inner end of the spring that co-operates with the dog of the movable support and holding means on the movable support for the inner end of the spring that co-operates with the dog of the immovable support.

In testimony whereof I affix my signature in presence of two witnesses.

FRANK MAGIDSON.
